No. 204,693. In Switzerland January 18, 1950

8 Claims. (Cl. 260—587)

1

The present invention has the object of providing a process for the preparation of α- and β-6-methyl-ionones.

This process is characterized in that 5-methyl-2-isopropyl-1,5,7-decatrienone-9 is subjected to a cyclization which yields conjointly stereoisomeric 6-methyl-α-ionones and 6-methyl-β-ionones.

The 5-methyl-2-isopropyl-1,5,7-decatrienone-9, Eb.0.03 mm. 110–115°; $d_{4}^{20}=0.894$; $n_{D}^{20}=1.5225$ can easily be synthesized by standard methods, such as described in Helvetica Chimica Acta 30, 1812 (1947), 32, 1354 (1949) and 33, 2019 (1950), in which the starting material dimethylheptenone is exchanged for 2-isopropyl-hexene-1-one-5 (Formula II), a product obtainable without difficulty from thujone, for example, according to Wallach (Annalen 275, 174 (1893), Berichte 30, 440 (1897), Simonsen, The Terpenes, vol. II, page 37, Second Edition).

It will now be indicated diagrammatically how this starting ketone can be prepared and how by cyclization it yields conjointly the α- and β-6-methyl-ionones (Formulae IV and V, respectively):

Nothing could make one expect hitherto that a substance like the ketone of the Formula III would cyclize according to the above scheme. In fact, contrary to all known examples (cyclization of pseudo-ionone, pseudo-ironone, etc.), the 1' carbon atom which takes part directly in the cyclization of the process according to the invention is not adjacent to a double bond. In spite of this, the ketone of the Formula III cyclizes readily and

with good yields particularly under the influence of acidic cyclization agents, this is to say of substances which when admixed solely to water, form liquids the pH value of which is lower than 5. Amongst these cyclization agents, sulphuric acid (~60%), phosphoric acid (~83%) and boron trifluoride give the best results. The concentration of the sulphuric acid may be between 58 to 62% (density 1.49 to 1.53), and the phosphoric acid may be of 80 to 87% concentration (density between 1.65 and 1.7).

The ketone of the Formula III (which is liquid) can exist in four different stereoisomeric forms owing to its double bonds at the carbon atoms 5 and 7. The commercial product obtained by synthesis is, however, a mixture in which one of the isomers may be more or less predominant according to the boiling point of the fraction utilized. The cyclization of this mixture yields the α- and β-6-methylionones which are, in turn, mixtures of stereoisomers. The relative proportions of the latter depend on the stereoisomerism of the starting ketone but it is also possible that they are influenced, at least partly, by the conditions in which the cyclization is carried out.

The direct product of the process according to the invention is a mixture of stereoisomers of the 6-methyl-α-ionone and of the 6-methyl-β-ionone. It does not differ or differs but little as regards its properties from the one obtained by the process described in U. S. patent application Serial No. 778,752 of October 9, 1947. The stereoisomers of either the 6-methyl-α-ionone or of the 6-methyl-β-ionone can be isolated from this di-

rect product as described in the said U. S. patent application.

This product, as well as the isolated 6-methyl-ionones can be utilized in the perfumery and in the cosmetics industry, wherever a particularly fine violet or orris root fragrance is desired.

Owing to the fact that the 5-methyl-2-isopropyl-1,5,7-decatrienone-9 (Formula III) used as a starting material can be readily synthesized, the process according to the present invention has a marked advantage over the one that consists in the cyclization of the η -methyl-pseudo-ionone, since the synthesis of the irone is thus found to be shortened and simplified.

It will now be described how the process according to the present invention can be carried out in practice:

Example 1 (phosphoric acid used as a cyclization agent)

Into 55 g. of ~83% phosphoric acid ($d=1.65$) cooled to between -4° and 0° C., 14 g. of 5-methyl-2-isopropyl-1,5,7-decatrienone-9 (boiling between 100° and 110° C. under 0.2 mm. Hg) are introduced at such a rate that the temperature does not exceed 0° C. The solution is maintained subsequently at 0° C. for 20 minutes, then heated to between 50° and 55° C. and maintained 15 more minutes at this temperature. It is mechanically agitated during the whole period of the operation. It is then poured on ice, extracted with ether, washed with water and with sodium carbonate, dried, concentrated and distilled.

One obtains 1.4 g. of foreruns and 9.5 g. of irone boiling between 87° and 89° C. under 0.2 mm. Hg. After purifying by means of Girard's reagent P, the constants of the irone obtained are:

$$d_4^{20}=0.9407-0.9360 \quad n_D^{20}=1.5004$$

Prior to purification, the irone has often a lower density (d_4^{20} minimum=0.930).

This product is a mixture of various stereoisomers of the α -irone type and of a few of the β -irone. The phenyl semi-carbazone melts at 172° C., its 2,4-dinitrophenyl hydrazone at 120° C. These two derivatives are identical with those yielded by the α -irone. In the mother liquors, stereoisomers may be found.

Example 2 (boron trifluoride used as cyclization agent)

Into a solution of 15.3 g. of 5-methyl-2-isopropyl-1,5,7-decatrienone-9 in 90 cc. of dry benzene cooled to 0° C., a rather rapid flow of BF_3 is introduced during about 30 minutes while stirring. The reaction manifests itself by a sudden increase in temperature which rises to $6-7^\circ$ C. The absorption of the boron trifluoride then ceases: amount absorbed 6.3 g. The irone- BF_3 complex is decomposed by means of 75 cc. of an 8% NaOH solution. The layers formed are separated, washed with 15 cc. of a 25% NaOH solution (while stirring for 1 hour), dried, concentrated and distilled. One obtains 11.7 g. of irone boiling at $83-87^\circ$ C. under 0.15 mm. Hg. Its constants are:

$$d_4^{20}=0.930-0.937 \quad n_D^{20}=1.5006-1.5042$$

This is a mixture of divers stereoisomers of the α -irone type and of a few of the β -irone. The phenyl semi-carbazone has a melting point of 172° C. which does not show any depression when mixed with that of the Example 1. One part melts below 159° C. and corresponds to different stereoisomers.

Instead of submitting to the cyclization mixtures of the various stereoisomers of the 5-methyl-2-isopropyl-1,5,7-decatrienone-9, the said various stereoisomers may be first enriched by fractional distillation, and the different fractions then subjected separately to a cyclization producing mixtures containing different quantities of the stereoisomeric 6-methyl- α -ionones and 6-methyl- β -ionones.

What I claim is:

1. A process for the preparation of α - and β -6-methyl-ionones, characterized in that 5-methyl-2-isopropyl-1,5,7-decatrienone-9 is subjected to a cyclization by action of an acidic medium which yields conjointly stereoisomeric 6-methyl- α -ionones and 6-methyl- β -ionones.

2. A process according to claim 1, in which the acidic medium is a medium which if dissolved in nine parts of water would give a 10% solution with a pH less than or equal to 5.

3. A process according to claim 2, characterized in that the said agent is sulphuric acid.

4. A process according to claim 2, characterized in that the said agent is phosphoric acid.

5. A process according to claim 2, characterized in that the said agent is boron trifluoride.

6. A process according to claim 3, characterized in that the said agent is sulphuric acid of a density between 1.49 and 1.53 (58-62%).

7. A process according to claim 4, characterized in that the said agent is phosphoric acid of a density between 1.65 and 1.7 (80-87%).

8. A process according to claim 1 for the preparation of selected mixtures of stereoisomeric α - and β -6-methyl-ionones, characterized in that the stereoisomeric 5-methyl-2-isopropyl-1,5,7-decatrienones-9 to be cyclised or selected according to boiling point and then subjected to a cyclization yielding a mixture of stereoisomeric 6-methyl- α -ionones and 6-methyl- β -ionones.

HEINRICH GRÜTTER.
